DESIGN FOR A LAWN MOWER

Sidney C. Lund, New York, N. Y., assignor to
Philip E. Wilcox, Inc., New York, N. Y., a corporation of New York

Application May 27, 1947, Serial No. 139,314

Term of patent 3½ years

(Cl. D40—1)

To all whom it may concern:

Be it known that I, Sidney C. Lund, a citizen of the United States, residing in the Borough of Manhattan, city, county, and State of New York, have invented a new, original, and ornamental Design for a Lawn Mower, of which the following is a specification, reference being had to the accompanying drawings, forming part thereof.

Fig. 1 is a front elevational view of a lawn mower, showing my new design and

Fig. 2 is a perspective view of the handle of the lawn mower shown in Fig. 1, the portion shown in broken lines being omitted for convenience in illustration.

The dominant features of my design reside in the portions illustrated in solid lines.

I claim:

The ornamental design for a lawn mower, as shown and described.

SIDNEY C. LUND.
